R. F. Bourne

ATTORNEY

UNITED STATES PATENT OFFICE.

GEORGE E. JENNINGS, OF MOUNT VERNON, NEW YORK.

SIGN.

956,857.

Specification of Letters Patent. Patented May 3, 1910.

Application filed May 20, 1908. Serial No. 497,163.

To all whom it may concern:

Be it known that I, GEORGE E. JENNINGS, a citizen of the United States, and resident of Mount Vernon, in the county of West-
5 chester and State of New York, have in-
vented certain new and useful Improvements
in Signs, of which the following is a speci-
fication.

The object of my invention is to provide
10 a sign or similar device which may be used
for advertising or analogous purposes, and
wherein the advertising matter will appear
as on an apparently moving background, al-
though the entire structure remains station-
15 ary and the advertising matter remains un-
changed and always visible in its entirety.

My invention comprises the novel details
of improvement that will be more fully here-
inafter set forth and then pointed out in the
20 claims.

Reference is to be had to the accompany-
ing drawings forming part hereof, wherein—

Figure 1 is a front elevation of a sign em-
bodying my invention; Fig. 2 is a vertical
25 section, substantially on the plane of the
line 2, 2 in Fig. 4; Fig. 3 is a face view
of the rear member or background, the front
member being removed, and Fig. 4 is a hori-
zontal section, substantially on the line 4, 4
30 in Fig. 1.

In the drawings the numeral 1 indicates
a front member or board, shown provided
with a plurality of openings 2, which are
35 shown in the form of relatively narrow elon-
gated slots cut or otherwise formed in mem-
ber 1. Said member may be formed by cut-
ting the openings 2 directly from a suitable
sheet or suitably built up board, or may be
40 formed of slats suitably connected together.
At 3 is a rear member or board shown in
solid form, located directly behind the front
member 1, to be seen through openings 2 of
the latter, and spaced at a suitable distance
45 from the front member 1. In the form
shown the front member 1 and the rear
member 2 are connected by suitable spacers
5, and said members may be supported in
any suitable manner, as by braces 6 holding
50 the front and rear members in a firm struc-
ture. Upon the front face of rear member
3 a suitable design is produced, such as by
painting thereon stripes 7 or other suitable
pattern, or such design may be applied by
55 pasting suitable paper or the like on the
rear member, and the outer face of the front
member, or the front faces of the slats, may

be painted or otherwise produced in colors
contrasting to the colors of the stripes or
design 7. Advertising or other matter may
be placed on the outer face of the front
member 1, and such matter may be painted
60 on the front member or may be made in
separate parts, such as of wood, metal or
the like, and laid on the forward face of the
front member, as indicated at 8.

A sign produced in accordance with my
invention may be located in any suitable po-
sition, where a person will observe the same
while passing the sign, as, for instance,
along the side of a railway track, on the side
70 of a building, or in other suitable position,
and when the observer passes or is carried
past the sign and while looking at the same
the parts of the stripes or design on the
rear member 3 which are visible through
75 the openings 2 of the front member 1, will
appear to move, while the advertising mat-
ter remains stationary and always visible in
its entirety. In other words, the device pro-
vides an apparently moving background
80 for the advertising matter, giving a pleasing
effect and one that will attract attention.
It will thus be understood that while the
parts of the sign remain stationary relative
85 to each other the movement of the observer
relatively to the sign causes the apparent
movement of parts of the sign, or an optical
illusion, without requiring any movement
90 of the sign or its parts. Hence the sign may
be installed and left without any attention
95 and yet the effect of a moving sign is pro-
duced.

My invention is not limited to the details
of construction shown and described, as the
same may be varied within the scope of the
100 appended claims without departing from
the spirit of my invention, and while I have
described my invention as applicable to use
for advertising signs it will be understood
that the same may be utilized for other
105 analogous purposes.

Having now described my invention what
I claim is:—

1. A sign comprising a member having a
plurality of openings, a permanently visible
design upon the front face of said member
independent of said openings, and a rear
member maintained at a distance from the
front member in fixed relation to the same
and provided with a design adapted to be
seen through said openings and arranged
in such relation to the openings in the front
110

member as to cause apparent movement of the visible parts of the rear design when an observer passes the sign, the first named design remaining unchanged in appearance at 5 all times from any angle of vision.

2. A sign comprising a front member provided with a plurality of similarly disposed openings, a design superimposed upon the front of said member and partially covering 10 said openings, and a rear member maintained at a distance from the front member in fixed relation to the same and provided with a suitable design adapted to be observed through said openings, the rear design being so spaced from the front member as to 15 be partially visible through the front openings at all angles of vision so as to cause apparent movement of the rear design behind said superimposed design by the changing relation of the solid portions of 20 the front member with respect to the rear design when an observer passes the sign.

3. A sign comprising a front member having a plurality of similarly disposed openings and the front face of which is provided 25 with a permanently visible design independent of said openings, and a rear member maintained at a distance from the front member in fixed relation to the same and provided on its forward face with a design hav-

ing lines and spaces at an angle to the openings of the front member adapted to be seen through said openings, the lines on the rear member being partially visible through the front openings and partially obscured 35 by the solid parts of the front member.

4. A sign comprising a front member provided with a plurality of parallel openings and solid portions located at an angle to the horizontal and provided on the front face 40 with a permanently visible design independent of said openings, a rear member located at a suitable distance from the front member and provided with a design having substantially parallel lines and spaces located at an angle to the openings and solid portions of the front member to cause the appearance of undulating motion of the visible parts of the rear design when an observer passes the sign all parts of the sign 45 being maintained in fixed relation to each other at all times.

Signed at New York city, in the county of New York and State of New York, this 19th day of May, A. D. 1909.

GEORGE E. JENNINGS.
